UNITED STATES PATENT OFFICE.

ANDREW YOUNG, OF BUFFALO, NEW YORK.

MARKING-PEN.

1,111,347.

Specification of Letters Patent. Patented Sept. 22, 1914.

Application filed July 16, 1912. Serial No. 709,700.

To all whom it may concern:

Be it known that I, ANDREW YOUNG, a citizen of the United States, residing at Buffalo, in the county of Erie and State of New York, have invented certain new and useful Improvements in Marking-Pens, of which the following is a specification.

The invention relates to pens used for marking shipping packages, writing signs, newspaper display writing, and the like, and has for its object the provision of a pen consisting of a single sheet of metal bent on itself and provided with a broad writing edge and an interposed ink retaining element, the two layers of the pen being slightly separated to form the ink reservoir, the pen being adapted to produce writing having heavy shaded portions.

The invention will be described in detail hereinafter and illustrated in the accompanying drawings, in which,

Figure 1, a plan view of a pen containing a filler consisting of a sheet of mica, celluloid or similar material; Fig. 2, a plan view of a pen and attached handle, one of the side members being broken away to show the ink retaining element interposed between the two members; Fig. 3, an edge view of the pen shown in Fig. 2; Fig. 4, a cross section on the line 5—5 of Fig. 2 looking in the direction of the arrow.

Referring to the drawing, in Fig. 1 the numeral 22 designates a marking pen made of a single piece of slightly flexible material bent upon itself to provide the body portion 22^a, and disposed between the two members of the pen is a strip or piece of mica, cellu-

loid, or similar material 21 for holding the ink between the two members of the pen.

As shown in Fig. 2, the two parallel members 31 are provided with an angular writing edge 35, the two members being bent on the line 36 and a pen holder 34 being connected between the two members, the pen holder being flattened and secured between the members 31 by means of rivets 32.

In Figs. 2, 3 and 4, a piece of mica, celluloid, or similar material 37 is secured between the two members and extends to the end of the writing edge 35.

A pen made in accordance with this invention is simple in construction and reliable and efficient in use.

Having thus described my invention, what I claim is:

A marking pen formed from a single piece of sheet flexible material, bent upon itself longitudinally to provide two flat, spaced parallel members having an open edge and an open feeding discharge outlet for the ink, the opposite edge of the pen being closed by the bend, the outlet end of the pen being disposed at an angle to the side and extending entirely across the pen and an ink retaining element or tongue disposed between the two members of the pen, said tongue being of less thickness than the distance between the parallel members of the pen.

In testimony whereof I affix my signature in presence of two witnesses.

ANDREW YOUNG.
